Patented Dec. 18, 1973

229,602

COMBINED CAN OPENER AND KNIFE SHARPENER

Alan F. Eckel, Chicago, Ill., assignor to Sears, Roebuck and Co., Chicago, Ill.

Filed Apr. 6, 1972, Ser. No. 241,891

Term of patent 14 years

Int. Cl. D7—99

U.S. Cl. D8—35

FIG. 4.

FIG. 5.

FIG. 6.

FIG. 1 is a perspective view of a combined can opener and knife sharpener showing my new design;

FIG. 2 is a front elevational view thereof;

FIG. 3 is a side elevational view thereof;

FIG. 4 is a side elevational view thereof, showing the side opposite to that shown in FIG. 3;

FIG. 5 is a rear elevational view thereof; and

FIG. 6 is a top plan view thereof.

The conventional power cord is fragmentarily shown in FIGS. 3, 4 and 6.

I claim:

The ornamental design for a combined can opener and knife sharpener, as shown and described.
